UNITED STATES PATENT OFFICE

JOHN ALLISON, OF SWISSVALE, PENNSYLVANIA, ASSIGNOR TO PITTSBURGH STEEL FOUNDRY CORPORATION, OF GLASSPORT, PENNSYLVANIA, A CORPORATION OF PENNSYLVANIA

CHARGING BOX

Application filed February 11, 1929. Serial No. 339,061.

This invention relates to charging boxes for introducing raw or scrap material into an open hearth furnace.

Heretofore such boxes have been subject to failure at their lifting end near the point where the charging bar employed for handling them is attached. This has been due to inability of the structure at the lifting end of the boxes to stand up under the very severe strains to which it is subjected. These boxes are comparatively long, and consequently the load of each is centered a considerable distance from the point where the box is supported, that is, the rear of the box where the charging bar is attached to it. Hence, there is a considerable strain on the charging-bar engaging structure, which has a tendency to, and frequently does, fracture the end of the box.

The object of the invention is to provide a charging box having a bar-receiving end which will effectively resist the severe strains to which it is subjected.

The invention will now be described in conjunction with the accompanying drawings, in which Fig. 1 is a plan view of a furnace charging box embodying the preferred form of my invention; Fig. 2 a vertical longitudinal central section through the box; and Fig. 3 an end view of the box.

Referring to the drawings, the charging box is illustrated as an integral steel casting having a bottom 1, side walls 2, a front end wall 3 and a rear or lifting end 4. The bottom and side walls of the box are preferably of increased thickness from the front to the rear of the box, thus considerably strengthening it where needed. The side walls and the bottom are extended rearwardly past the rear end of the box, which is a vertical end wall 5, and all terminate in a slotted charging-bar-receiving end wall 6. Between side walls 2 and rear wall 5 in each of the upper rear corners of the box there is provided a horizontally disposed brace 10, and in the bottom of the box between the floor 1 and the rear wall 5 there are provided a plurality of vertically disposed braces 20 which reinforce the rear portion of the box and prevent the forward portion from pulling

away from the rear wall 5 when a heavy load is being carried in the box or when the box is being forced into the furnace.

Directly forward of wall 6, and forming with it a girder-like structure, there is provided a second slotted charging-bar-receiving end wall 7, which also forms the back wall of a pocket 8 arranged in the end of the box for receiving a charging bar, not shown. Spaced forwardly of wall 7 and rearwardly of wall 5, there is another cross wall 9 which forms the front wall of charging-bar-receiving pocket 8, and with wall 5 forms a box-like structure similar to the structure provided at the rear of pocket 8 by end walls 6 and 7. These two box-like structures further increase the strength and rigidity of the lifting end portion of the box and make it capable of withstanding the excessive strains exerted on the box due to the lever action of the box load. The cross walls are rigidly held in place by longitudinal walls 11 and 12 and top walls 13 and 14, respectively, which act as binders or struts between the girder-like walls. In addition, web-like sections 15 and 16 are formed between rear end wall 5 of the box proper and wall 6 at the end of the lifting portion of the box to further increase the strength and rigidity of its lifting end.

As illustrated, pocket 8 formed by cross walls 7 and 9 are shaped to receive a charging bar of a well known type, having a reversible wedge shaped head and a movable box engaging cross lug. Wall 9 of pocket 8 is inclined forwardly from the bottom upward to receive the inclined face of such a charging bar head, and walls 6 and 7 are provided with a vertical slot 19 for receiving the handle of the charging bar. Arranged crosswise of walls 6 and 7 about the center of slot 19 there are provided cross slots 21 which receive a movable lug provided on the charging bar to prevent it from becoming uncoupled when the box is unloaded. However, the end may be formed to receive other well-known or desired types of charging bar head.

According to the provisions of the patent statutes, I have explained the principle and operation of my invention, and have illus-

trated and described what I now consider to represent its best embodiment. However, I desire to have it understood that, within the scope of the appended claims, the invention may be practiced otherwise than as specifically illustrated and described.

I claim as my invention:

1. An elongate furnace-charging box having side and end walls and a bottom, the rear of the box being provided beyond its end wall with a vertically disposed charging-bar-receiving pocket surrounded by vertically disposed double walls spaced from each other.
2. An elongate furnace-charging box having side and end walls and a bottom, the rear of the box being provided beyond its end wall with a charging-bar-receiving pocket surrounded by vertically disposed double walls spaced from each other, and the side walls of the box being extended beyond its rear end wall to form the outer walls of the sides of said pocket.
3. An elongate furnace-charging box having side and end walls and a bottom, the rear of the box being provided beyond its end wall with a charging-bar-receiving pocket surrounded by vertically disposed double walls spaced from each other, and the side walls and bottom of the box being extended beyond its rear end wall to form the outer walls of the sides and bottom of said pocket.
4. An elongate furnace charging box having side and end walls and a bottom, reinforcing horizontally disposed braces arranged between said side walls and rear end wall at the upper corners of the box and between said rear end wall and said bottom, and the rear of the box being provided beyond its end with a vertically disposed charging-bar-receiving pocket surrounded by vertically disposed double walls spaced from each other.
5. An elongate furnace charging box having side and end walls and a bottom, said side walls and bottom being tapered from the front to the rear of the box, and the rear of the box being provided beyond its end wall with a vertically disposed charging-bar-receiving pocket surrounded by vertically disposed double walls spaced from each other, and joined at their top, bottom and sides by other walls with the top, bottom and sides of the box.
6. An elongate furnace charging box having side and end walls and a bottom, said side walls and bottom being tapered from the front to the rear of the box, horizontally disposed reinforcing braces arranged between said side walls and rear end wall at the rear upper corners of the box and vertically disposed braces arranged in spaced relation to one another between said rear end wall and said bottom, and the rear of the box being provided beyond its end wall with a charging-bar-receiving pocket surrounded by verti-

cally disposed double walls spaced from each other.

7. An elongate furnace charging box having side and end walls and a bottom, the rear of the box being provided beyond its end wall with a charging-bar-receiving pocket surrounded by vertically disposed double walls spaced from each other, the side walls and bottom of the box being extended beyond its rear end wall to form the outer walls of the sides and bottom of said pocket, and an upper wall extended rearwardly from the top of the box joining the upper ends of said vertically disposed pocket-forming walls.

In testimony whereof, I sign my name.

JOHN ALLISON.
